SUSPENSION FOR CRANE BOOMS

Trevor O. Davidson, Milwaukee, Wis., assignor to
 Bucyrus-Erie Company, South Milwaukee, Wis.,
 a corporation of Delaware

Application November 13, 1943, Serial No. 510,098

3 Claims. (Cl. 212—144)

My invention relates to new and useful improvements in suspensions for crane booms, more particularly for the very long booms on that type of crane known as dragline excavators.

It has been found that, in the case of a long slender inclined boom, suspended by guys extending from an A-frame on the base of the machine to the outer point of the boom, there is a distinct sag in the middle of the boom, when the boom is not under load. When a load is added to the hoist rope which passes from a winch on the base of the machine, thence over a sheave at the point of the boom, the end-to-end compression in the boom, due to the resultant of the tension in the hoist rope and the suspension guys, greatly and dangerously increases this downward bend at the middle of the boom.

To obviate this sag and bend, the conventional expedient has been to run a second set of guys from the A-frame to the middle of the boom. This eliminates the above discussed initial sag and consequent bend, but only so long as the two sets of guys remain in perfect and exact relative adjustment. If the center guys become disproportionately stretched, they do not prevent the discussed tendencies. Whereas, if the long guys become disproportionately stretched, the center guys will impose an initial upward bend in the boom, which will become greatly and dangerously increased with the addition of a load on the hoist rope; and there will be nothing to resist this bend.

Accordingly, it is the principal object of my invention to devise a boom suspension, effective automatically to prevent excessive and dangerous bending under load, and yet without requiring fine adjustment.

In addition to my principal object, above stated, I have worked out a number of novel and useful details, which will be readily evident as the description progresses.

My invention consists in the novel parts and in the combination and arrangement thereof, which are defined in the appended claims, and of which one embodiment is exemplified in the accompanying drawing, which is hereinafter particularly described and explained.

Throughout the description the same reference number is applied to the same member or to similar members.

The single figure is a perspective view, taken from slightly above and slightly to the rear, showing somewhat conventionalized my boom and its suspension.

Referring to this figure, we see that 11 is the

main frame of a crane. Pivoted to the front thereof, and extending forwardly diagonally upward, is a boom 12. Also pivoted to the front of the main frame 11, and extending forwardly diagonally upward at a steeper inclination, is a strut 13. This strut is supported by boom-hoist ropes 14 from the top of A-frame 15.

The strut 13 need not be separately pivoted to the main frame. As shown, its foot is integral with the foot of the boom, inasmuch as the flexibility of these two elements is sufficient to produce the same effect (within the scope of their very limited relative movement) as though they were separately pivoted to the main frame.

15 Fixed-length guys 16 extend from the top of the strut to the outer end of the boom 12. Short suspension members 17 are supported by these guys at about their mid point, and in turn support the middle of the boom.

20 Initially there will be a slight sag in the middle of the boom, and a resulting angle in guys 16 at the point of attachment of the short suspension members 17 thereto.

25 The length of these suspension members is so selected that, under the influence of the normal maximum expected load, the increased tension in the guys will flatten the angle in the guys sufficiently to straighten out the sag in the boom exactly, or practically so.

30 One by-product of my invention is, of course, to reduce the whip in the boom under live loads, but this advantage is also attained by the prior art device discussed earlier herein.

35 The guys need not be ropes; other sorts of tension members, capable of angular, or even non-angular, bending at the point of attachment of the suspension members, would suffice, although ropes are simpler, being easier to rig and adjust. And similarly the suspension members themselves need not be stiff, since they carry merely tension.

The A-frame need not be in A-frame form; hence the use of the word "A-frame" in the claims intends an A-frame or equivalent.

40 45 The importance of having the guys 16 be fixed-length should be stressed. For if these guys were merely reaches of the boom-hoist ropes 14, it would be nearly impossible to maintain a proper adjustment of relative lengths.

50 55 The interposition of strut 13 is highly advisable. Its presence not only imparts an increased upward component on the outer end of the boom during operations; but also maintains this component during raising and lowering the boom, whereas this component would nearly vanish in

fully lowered position, if the strut were omitted.

Furthermore, the presence of the strut facilitates a permanent adjustment of the proper relative lengths of guys 16 and suspension members 17.

The hoist rope 18 runs from a winch 19 on the main frame 11, over a sheave 20 on the strut 13, thence over a sheave 21 at the outer end of the boom, and thence downwardly to the load (not shown) to be lifted thereby. Other fairlead means than sheave 20 could be employed, or such means could be omitted.

Having now described and illustrated one form of my invention, I wish it to be understood that my invention is not to be limited to the specific form or arrangement of parts herein described and shown, except as specifically limited by my claims.

I claim:

1. In a suspension for a long slender upwardly inclined crane boom, the combination of an A-frame adjacent the foot of the boom; an upwardly projecting strut, between the A-frame and the boom, and pivotally mounted adjacent the foot of the boom; fixed-length guys from the upper end of the strut to the outer end of the boom; means for supporting the strut from the A-frame; and fixed-length suspension means for the boom, extending downwardly from the middle of the guys to the middle of the boom, so as to permit

20
25
30

an initial sag in the boom, but so as to straighten the boom, when the guys straighten under influence of a load on the outer end of the boom; the length of said suspension means being slightly less than the distance, from its point of attachment to the boom, to a straight line drawn between the two ends of the guys, when the boom is not under load.

2. In a suspension for a long slender upwardly inclined crane boom, the combination of an upwardly projecting member adjacent the foot of the boom; fixed-length guys from the upper end of the upwardly projecting member to the outer end of the boom; means for supporting the upwardly projecting member; and fixed-length suspension means for the boom, extending downwardly from the middle of the guys to the middle of the boom, so as to permit an initial sag in the boom, but so as to straighten the boom, when the guys straighten under influence of a load on the outer end of the boom; the length of said suspension means being slightly less than the distance, from its point of attachment to the boom, to a straight line drawn between the two ends of the guys, when the boom is not under load.

3. A suspension according to claim 1, further characterized by the fact that the means for supporting the strut is variable in length, for varying the inclination of the boom.

TREVOR O. DAVIDSON.
